UNITED STATES PATENT OFFICE.

CLIFFORD E. PAINE, OF CHICAGO, ILLINOIS, ASSIGNOR OF ONE-FOURTH TO LUTHER JOHNS, OF CHICAGO, ILLINOIS.

BRIDGE.

1,093,202.

Specification of Letters Patent. Patented Apr. 14, 1914.

Application filed July 5, 1913. Serial No. 777,509.

To all whom it may concern:

Be it known that I, CLIFFORD E. PAINE, a citizen of the United States, residing at Chicago, in the county of Cook and State of Illinois, have invented certain new and useful Improvements in Bridges, of which the following is a specification.

My invention relates to bridges, and has more particular reference to bridges of the 10 lift type in which a span or portion of the bridge is raised.

It is not broadly new to provide lift bridges in which a system of levers and weights is employed for counterbalancing 15 the span or a portion thereof when the same is being raised or lowered. Various objections exist in the counterbalancing means heretofore suggested, however, as for instance the inclusion therewith of a plurality 20 of counterbalancing weights in each device and the necessity for shifting at least one of such weights in order to compensate for the actual swing of the lifting or counterbalancing lever pivoted on a fixed support. Other 25 objections are the large number of pivotal connections employed, all producing friction and wear and entailing large expense in the repair of broken or worn out parts as well as in the initial costs. Still other no- 30 table objections are necessities for long link connections for shifting the counterweight, which links owing to their great length, must be made objectionably heavy and sometimes be well braced, thus adding greatly 35 to the cost as well as to the objection of weight and a multiplicity of parts. Further objections are to the appearance of hitherto suggested structures, and also to the difficulties experienced in the construction 40 and arrangement of details to avoid the interference of operative parts.

The principal objects of the present invention are to provide a counterbalance for bridges and the like in which the weight of 45 the counterbalancing mechanism as well as the load to be lifted may be counterbalanced by a single counterweight; further to provide such apparatus in which such balance is maintained in all operative positions of 50 the parts, and notably without the necessity of shifting a counterweight relative to its supporting member.

A further object is to provide a counter- 55 balancing system of levers, etc. by which when the bridge is moved vertically the

counterweight as a whole also moves vertically or approximately vertically throughout its entire travel, as distinguished from other proposed devices in which a single weight or one of a plurality of the weights 60 used moves in a curved path of travel.

Further objects are to provide a counterbalancing system which is simple of construction, of comparatively few parts, having few pivotal connections, which may be 65 made in accordance with the principles of good engineering, and one which does not require the inclusion of poor structural details in order to avoid interference of relatively moving parts; to provide a counterbalancing system in which the counterweight may be fixed to or upon its supporting member, or may be suspended as a pendant therefrom, all without prejudice to the perfect 70 balance of the structure in all operative positions of the same. 75

General objects are to provide a counterbalancing system and a bridge having a counterbalancing device or devices in which the counterbalancing structure is of simple 80 and economical design, manufacture and repair, which is strong and durable, effective in operation, and which is pleasing in outline and general appearance.

In the drawings which accompany and 85 form a part of this application I have illustrated certain preferred and modified embodiments of my improvements as applied to a bridge of the vertical lift type, the parts being shown diagrammatically in a 90 manner well suited to a clear understanding of the invention herein set forth.

In these drawings Figure 1 is a side elevation of a bridge showing the preferred form of counterbalancing apparatus adjacent to each end thereof, the vertically movable span being shown in lowered position; Fig. 2 is a similar view to that of Fig. 1, but showing the span raised; Fig. 3 is a top plan showing a pair of counterbalance levers adjacent to each end of the movable span, each pair carrying a single counterweight; Fig. 4 is a side view showing a modified application in which the span and counterweight are in reverse arrangement 105 from that shown in Fig. 1; Fig. 5 is an enlarged diagrammatic side elevation of one of the counterbalancing devices shown in Fig. 1.

Referring to Fig. 1 the vertically movable 110

span 20 is shown as resting on piers 21 which also support the towers or fixed supports 22 adjacent to the ends of the movable span and which supports are provided at 5 their upper ends respectively with a trunnion bearing for a trunnion 30. It is understood that bridges of this type usually have four counterbalancing devices—a pair at either end of the movable span—as indicated in Fig. 3. The counterbalancing devices respectively may conveniently be connected to the span 20 at a point 25 on the truss 24, although the connections may be made at other suitable points. Upon the 10 support 22 there may be arranged a toothed rack 26 extending from the bottom to substantially the highest point thereof, and on the bridge span 20 I have conventionally illustrated means for raising and lowering 15 the span, comprising the toothed wheels or pinions 27 adapted to engage the teeth of the racks 26, the pinions being rotatable by means of the shaft 28 extending from one end of the bridge to the other and itself 20 suitably rotated by driving mechanism 29, a similar shaft, pinions, etc. being positioned on the opposite side of the span, the two driving shafts being adapted by means of the cross shaft 28' (Fig. 3) to raise or lower 25 the four corners of the span simultaneously and with equal movement. The span may be suitably guided in its vertical movements by sliding or rolling connections in engagement with the fixed supports, the supports 30 35 22 (see Fig. 5) being shown as provided with guides 22^a adapted to be engaged by the shoe 20^a on the span 20.

In the preferred arrangement illustrated a link 31 is pivotally mounted on the trunnion 30, which link at its upper end is pivoted at 32 to the counterbalance lever 33 which, as shown, extends on either side of the pivotal connection 32. The lever 33 40 may suitably be in the form of a truss as 45 illustrated in the drawings. A connecting lever 34 is pivotally attached to one end of the lever 33, as at 35, the other end of the lever 34 being pivotally connected to the truss 24 by the pin 25. A link 36 is pivoted 50 upon the main trunnion 30 and is also pivotally connected to the lever 34 at a point 37 the same distance from the center of the pivotal point 35 as the center of the pivot 32 is spaced from the center of the trunnion 30, the distance between the points 30 and 55 37 being the same as that between the points 32 and 35.

It will be noted that the arrangement of the parts hereinabove described is such that 60 lines joining the pivotal centers 30, 32, 35 and 37 form a parallelogram. If the line 35—32 is produced it will intersect a line produced through points 25—30 at a point as 41. It is a property of this arrangement 65 that the three points 41, 30 and 25 will al-

ways remain in a straight line in all operative positions of the device. If the links 31 and 36 and the levers 33 and 34 were themselves without weight a counterweight fixed upon lever 33 with its center of gravity at the point 41 and being of a weight sufficient to balance a constant weight applied at the point 25 would perfectly balance such weight in all of the operative positions, and this whether the point 25 be moved vertically, horizontally, or with a combination of movements vertical and horizontal. Owing, however, to the weight of the links and levers mentioned additional counterweight must be added to counterbalance these parts. 70

The weight and location of the counterweight may be practically determined according to methods well understood in the art. For the purposes of this description, we will assume that a weight W is 80 applied at the point 25. For center of gravity calculations we may consider a proper portion of the weight of link 31 as concentrated at the point 32 and the remainder as concentrated at the fixed point 30. Likewise a portion of the weight of link 36 may be considered as concentrated at 85 37 and the remainder at the fixed point 30. A part of said portion considered as concentrated at 37 may now be considered 90 as concentrated at 35 and the remainder at 25. A proper portion of the weight of member 34 is considered as concentrated at 95 35 and the remainder at 25. The weight of the counterbalance lever 33 is concentrated at the center of gravity of said lever, assumed for the purpose of this description as at point 43. Summarizing we have the weight of the various members of the device 100 properly proportioned to the points of concentration 30, 32, 35, 25 and 43. The part considered concentrated at 30 obviously does not require to be counterbalanced. The portion considered as concentrated at 25 may be added to the weight W and considered as additional weight at 25 to be counterbalanced. The remainder of the weight of the links and levers mentioned is now concentrated, as hereinabove shown, at the points 32, 35 105 and 43, all bearing a fixed relation to the counterbalance lever 33. The center of gravity of the weights concentrated at points 32, 35 and 43 may readily be computed, and, for the purposes of this description, will be assumed as being at the 110 point 44. 115

The counterweight 40 may be imagined as divided into two parts, as 40^a and 40^b. The portion 40^a is so selected that its center of gravity, as point 42, is on a line 120 drawn through the points 44 and 41, and the resultant of the weight at 44 and the weight of the portion 40^a is a weight equal to the sum of the two (40^a plus 44) and is concentrated at point 41. This sum is now ad- 125 130

ded to the remainder of the counterweight, namely the portion 40^b, said portion 40^b having its center of gravity at 41, giving a total weight concentrated at 41 equal to the sum of 40^a plus 44 plus 40^b, to balance the weight at 25 which includes W plus a certain amount of the link and lever weight as hereinabove described. The balance obtained as thus set forth will be maintained in all operative positions of the device.

It is to be noted that in the above exemplary discussion of a method for determining the size and location of the counterweight all of the forces are considered as acting in the same plane. Persons skilled in the art will be able readily to make practical computations for any particular application of the invention disclosed. It is thus to be observed that one counterweight suffices, in the application of my invention, to the counterbalancing of the weight applied at 25 as well as the weight of the counterbalance structure, said counterweight as a whole being fixed in such position that it has an approximately vertical movement when the counterbalanced weight is moved vertically, the point 41 always moving in a vertical line.

It is to be understood that in practical construction the counterweight 40 may extend from one counterbalance lever 33 of the pair, as shown in Fig. 3, to the other, and that for computation half of the weight of the span may be considered the proper portion of the weight to be counterbalanced by the two counterbalancing structures at one end of the span 20. Should it be desired to compute the weight necessary to be applied on one counterbalance lever alone, one-fourth of the weight of the span may be considered the proper portion of the weight so to be counterbalanced, assuming, of course, that the movable span is symmetrical constructed so that its center of gravity is equidistant from each of the four points of support. Each counterbalancing device may, of course, carry a counterweight independently of any other co-operating counterbalancing device.

In Fig. 4 of the drawings the free end of the connection lever 33^a is attached to the span 20 at 25, the counterweight 40^a being applied to the counterbalance lever 34^a. This arrangement embodies the same mechanical features as that shown in Fig. 1 and will not require further separate description.

While I have illustrated and described preferred and modified embodiments of these improvements in their application to a lift bridge, the invention is not limited to the embodiments shown and described or to the application herein set forth, as changes may be made in details of construction, arrangement and application, all with-

in the principle of the mechanics employed and within the scope of the invention; and all such changes, modifications and adaptations are contemplated by me as fall within the scope of the appended claims.

76

I claim:

1. In a counterbalance for a bridge having a vertically movable part, the combination with such vertically movable part, of a fixed support, a plurality of links having a common pivotal axis mounted on said fixed support, a lever pivoted to each of said links, said levers being pivoted together, one of said levers being connected operatively to said vertically movable part, and a counterbalancing weight attached to another of said levers and adapted to counterbalance a proper portion of the weight of such vertically movable part.

2. In a counterbalance for a bridge having a vertically movable part, the combination with such vertically movable part, of a fixed support having a pivot, a plurality of levers operatively maintained in spaced relation to said pivot by a plurality of links mounted on said pivot, said levers being pivoted together, one of said levers being operatively connected to said vertically movable part, and a counterweight on one of said levers adapted to counterbalance a proper portion of the weight of such vertically movable part.

3. In a bridge, the combination of a vertically movable span, a fixed support, a plurality of links pivotally mounted on a common axis on said fixed support, a plurality of levers pivotally carried by said links, said levers being pivoted together, a counterbalancing weight on one of said levers adapted to counterbalance a proper portion of the weight of said vertically movable span, and a connection between one of said levers and said span.

4. In a bridge, the combination of a vertically movable span, a fixed support adjacent to said span, two levers pivoted together and each lever pivoted to one of two links respectively, said links being pivotally mounted on a common axis on said fixed support, a connection between said associated levers and links and said span, and a counterbalancing weight associated with one of said levers and adapted to counterbalance a proper portion of the weight of said span.

5. In a bridge, the combination of a vertically movable span, a plurality of fixed supports adjacent to said span, and a counterbalancing mechanism associated with each support, one of said counterbalancing mechanisms comprising a plurality of links pivoted on a common axis on one of said fixed supports, a counterbalance lever pivotally connected to one of said links, and a connecting lever pivotally connect-

ed to another of said links, said levers being pivotally connected together, said links and levers forming a parallelogram, a counterbalancing weight rigidly attached to said counterbalance lever, said connecting levers being pivotally connected to said span, said counterbalancing weight being adapted to counterbalance both the weight of the span to be counterbalanced and the weight of said links and levers in all operative positions as the span is vertically moved, and means for vertically moving said span.

6. In a bridge, the combination of a vertically movable span, a fixed support adjacent thereto, a plurality of links and levers pivoted together forming a unitary parallelogram structure, two of said links being pivotally mounted with a common axis on said fixed support, the arrangement being such that said unitary structure is adapted to revolve through a partial orbit about said fixed support, a counterbalancing weight on one of said levers adapted to counterbalance the weight of said unitary structure and also a proper portion of the weight of said span, and a connection between one of said levers and said span.

7. In a bridge, the combination of a vertically movable span, counterbalancing mechanism therewith, a fixed support adjacent to said span, a pivot on said fixed support adapted to carry the weight of the shifting counterbalancing mechanism and the weight of the span to be counterbalanced thereby, said counterbalancing mechanism comprising a counterbalance lever spaced from said pivot in all operative positions of said lever, means (including a link connecting piece directly between said pivot and said lever) adapted to maintain said lever in such spaced relation to said pivot that said lever moves bodily through a partial orbit about said pivot when the span is raised or lowered, said lever having a counterbalance weight connected therewith, and means operatively connecting said lever and associated parts to said span, said counterbalance weight being adapted to counterbalance the weight of the span to be counterbalanced by said counterbalancing mechanism.

8. In a bridge and counterbalancing mechanism therewith, the combination of a vertically movable span, a fixed support adjacent to the span, a pivot on said fixed support adapted to carry a weight including a proper portion of the total weight of the span to be counterbalanced, a counterbalance lever, means pivoted on said fixed support and operatively connected with said counterbalance lever adapted to maintain said lever in spaced relation to said pivot in all operative positions of the lever, a single counterweight connected with said counter-

balance lever, said counterweight being adapted to counterbalance both the weight of the counterbalancing device to be counterbalanced and that portion of the weight of the span as is to be counterbalanced by said counterbalancing device, a connecting element operatively connecting the counterbalancing mechanism and said span, the arrangement being such that the center of gravity of the shifting counterbalancing elements and of the weight of the span as concentrated at the point of connection between said connecting element and said span is at said pivot in all operative positions of the counterbalancing device.

9. In a bridge, the combination of a fixed support, a movable span, a counterbalance lever mounted to rock in spaced relation to said fixed support, means connecting said fixed support and said lever, said means maintaining said lever in spaced relation to said support in all operative positions of the device, means connecting said lever and said span, said means having a pivotal connection with said span, a single counterweight rigidly connected with said lever, said weight being adapted to counterbalance both the counterbalance mechanism and the load to be counterbalanced, the arrangement being such that when the counterbalancing weight descends with a point in the vicinity of its center of gravity moving in a vertical line said pivotal connection also moves in a vertical line, and means for vertically moving said span.

10. In a bridge, the combination of a movable span, a fixed support adjacent thereto, two links and two levers pivoted together and forming a parallelogram structure, one corner of said parallelogram structure being pivotally mounted upon said fixed support, a single counterweight attached to one of the lever members of said parallelogram, and a connection between the other of said levers and said span, said counterweight being adapted to counterbalance in all operative positions of the device both the weight of the span to be counterbalanced and the weight of the counterbalancing links and levers.

11. In a counterbalance for a bridge, the combination of a movable span, a fixed support adjacent thereto, two adjacent links and two adjacent levers all pivotally connected together to form a parallelogram structure, the common pivot of said adjacent links of said parallelogram structure being mounted upon said fixed support, one of said levers of said parallelogram structure being extended beyond one of the pivotal points thereon, and a counterweight on said extension, the other of said levers being extended beyond one of the pivotal points thereon, and means for connecting said last mentioned extension to said movable span,

the arrangement being such that the reaction on the fixed support is constant and in a vertical direction in all operative positions of the device.

- 5 12. In a bridge and counterbalancing mechanism therewith, the combination of a vertically movable span, a fixed support adjacent to said span, two links mounted to move upon a common axis upon said fixed support, a connection lever having means whereby said lever may be pivotally connected to said span, a counterbalance lever pivotally connected to one of said links, said connection lever being pivotally connected to said span, to said counterbalance lever and also to the other of said links, said connected links and levers forming a parallelogram structure in all operative positions of the device, said parallelogram structure being adapted to move bodily upon one corner thereof at said first mentioned common axis, each of said levers having an extension thereof beyond said parallelogram structure, a counterbalancing weight on the extension of said counterbalance lever, the extension of the other lever being pivotally connected to said span, the arrangement being such that the weight of the span to be counterbalanced by said
- 10 15 20 25 30

13. In a bridge, the combination of a vertically movable span and counterbalancing apparatus therewith, said apparatus comprising a pair of fixed supports adjacent to each end of said span, counterbalancing mechanism on each of said supports and connected to said span, each of said counterbalancing mechanisms being adapted to counterbalance its proper portion of the weight of the span as it is raised and lowered, one of said counterbalancing mechanisms comprising two links pivotally mounted to rock on a common axis on its fixed support, a counterbalance lever pivotally mounted on one of said links, a second lever pivotally connected to said span, to the other of said links, and also to said counterbalance lever, said links and levers being connected together and forming a parallelogram structure in all operative positions of the device, a counterweight connected to said counterbalance lever, said counterweight being adapted to counterbalance the weight of said links and levers to be counterbalanced and also a proper portion of the weight of said span to be counterbalanced by said counterbalancing apparatus, and means for vertically moving said span.
